CLIFTON WEST, OF LONDON, ENGLAND.

PROJECTILE.

1,174,644.

Specification of Letters Patent.

Patented Mar. 7, 1916.

Application filed July 13, 1914. Serial No. 850,600.

To all whom it may concern:

Be it known that I, CLIFTON WEST, a subject of the King of Great Britain, residing at London, England, have invented new and useful Improvements in Projectiles, of which the following is a specification.

This invention relates to projectiles of any suitable size of the kind which are more especially intended for the destruction of dirigible air-ships, balloons, and the like, by the employment of which not only will the envelope of the balloon be penetrated and torn, but the gas contained therein will be ignited and exploded, thereby insuring the complete and immediate destruction of the air-ship or balloon. For this purpose projectiles have been furnished with extensible arms for gripping and tearing the balloon, and also with devices for igniting the balloon gases.

According to this invention the igniter produces sparks or the like by the frictional contact of opposing parts.

In the accompanying drawings Figure 1 is a longitudinal section of a projectile illustrating one method of carrying out my invention; Fig. 2 is a similar view to Fig. 1 but illustrating a modified method for effecting the same purpose.

Similar letters of reference relate to like parts in all the figures of the drawings.

In Fig. 1 *a* is the body of the projectile, *b* the nose or fore-part thereof, *c* a block suitably connected to the body *a*, and having any convenient number of holes disposed in a circular path and into which are placed rods *d* of spark-producing or pyrophoric alloy, for example, supported by and forced outward by helical springs *e*. The nose or

fore-part *b* is furnished with helical or screw-shaped outer surfaces *f*, and is rotatably mounted on the block *c* by means of a backwardly projecting pin or stem *g*, which may be retained in position by means of a set-screw *h* or the like engaging with an annular groove *i* therein in a well known manner. A space *j* is provided between the front end of the body *a* and the rear of the nose or fore-part *b*, and the adjacent surface *x* of the latter, which is in contact with the outer ends of the pyrophoric rods *d*, is milled or roughened. A hole closed by a screw-plug *k*, may be provided in the rear end of the projectile through which a screw-

purpose of screwing or unscrewing the block *c*.

It will be understood that when the projectile is fired, the rods *d* will be carried around therewith, and the nose or fore-part *b* with its pin or stem *g*, being free to rotate independently of the body *a* of the projectile, and by its screw-shaped outer surfaces *f* being retarded or caused to rotate in the opposite direction to that of the body *a*, the friction thereby set up between the milled or roughened surface *x* and the outer ends of the rods *d* will cause a continuous stream of sparks or flame to be emitted and projected outward through the space *j*. Holes *m* may be formed in the nose *b* as shown, through which air will be caused to pass into the space *j* and assist in dispersing in a radial direction the sparks or flame as they are formed. This emission of sparks or flame enables the course of the projectile to be traced during its flight, and may be employed for this purpose if desired. But if it is required that no sparks, flashes, or flames shall be emitted until the projectile has attained a certain distance, the action of the frictional contact of the spark, flash, or flame-producing medium may be delayed by providing the outer ends of the rods *d* for example with a protecting shield *85* which it will be necessary to penetrate or wear away before the pyrophoric alloy or the like is reached, and consequently no sparks, flashes, or flames will be produced during the early part of the flight of the projectile, or until it has arrived within a predetermined distance of the air-ship balloon, or other point of destination.

In some cases the projectile upon being fired, will bring a suitably roughened frictional rotating or otherwise rapidly moving surface into contact with a relatively stationary spark-producing or pyrophoric alloy, flint, or other suitable spark, flash or flame producing medium; or the said medium may be rapidly rotated or otherwise moved in contact with the said relatively stationary frictional surface; or the two may be rotated or moved in opposite directions. For example, in Fig. 2 the rods *d* are shown mounted in holes in the fore-part or nose *b*, which is rotatably mounted upon the body *a* of the projectile by means of the central pin *g*, the outer ends of the rods *d* bearing upon the milled or roughened surface *x* of

the forward end of the body *a* of the projectile. In this case the springs *e* shown in Fig. 1 may be dispensed with, as the nose *b* in which the rods *d* are mounted will be constantly urged toward the body *a* during the flight of the projectile.

In some cases a quantity of suitable gas or inflammable vapor in a state of compression may be stored within the projectile, and suitable piercing devices may be provided, so that a continuous fine stream of the gas or vapor may be allowed to escape, mix with air, and be ignited by the means hereinbefore described, upon the said projectile coming in contact with the balloon envelop or other point of destination. A method of carrying this into effect is shown in dotted lines in Fig. 1, wherein 2 represents the receptacle containing the compressed gas, in the top of which is provided a seal or disk 3 which is pierced by the "set-back" imparted to the plug or rod 5 on the projectile being discharged from the gun, the rod 5 being maintained within its guide-tube 6, in the position shown, by friction or otherwise. On the projectile being discharged, the rod 5 is forced backward and pierces or fractures the disk 3, whereby the gas is free to escape through the holes 7 to mix with the atmosphere or other gas pervading the exterior.

I have found that pyrophoric alloy, being unaffected by fire or water, and only firing by friction, gives good results as a spark, flash, or flame-producing medium, but I do not desire to limit myself to the employment of such alloy. Neither do I limit myself to the use of such alloy in rod form

as illustrated, as it may be employed in the form of tubes, blocks, rings, or other like shapes or surfaces according to requirements.

Claims:

1. A projectile provided with devices for creating igniting sparks by the frictional contact of opposing parts, comprising an independent rotatable nose with helical outer surfaces thereon, a roughened surface, and pyrophoric rods urged against said surface by springs, substantially as described.

2. A projectile provided with devices for creating igniting sparks by the frictional contact of opposing parts, comprising an independent rotatable nose with helical outer surfaces thereon, a roughened surface and pyrophoric rods urged against said surface, substantially as described.

3. A projectile provided with devices for creating igniting sparks by the frictional contact of opposing parts, comprising an independent rotatable nose with helical outer surfaces thereon, a roughened surface, and pyrophoric rods urged against said surface by springs, in combination with a gas reservoir and a rod operated by the "set back" imparted to the said rod on discharge of the projectile to pierce the said reservoir, substantially as described.

In testimony whereof I have signed my name to this specification in the presence of two subscribing witnesses.

CLIFTON WEST.
